United States Patent

Des. 236,330
Patented Aug. 19, 1975

236,330

REPRODUCTION MACHINE STACKING CART

Jacob W. Patla, Fairport, N.Y., assignor to
Xerox Corporation, Stamford, Conn.

Filed Dec. 27, 1973, Ser. No. 428,935

Term of patent 14 years

Int. Cl. D12—02

U.S. Cl. D12—28

FIG. 1

FIG. 1 is a front perspective view of a reproduction machine stacking cart showing my new and ornamental design;

FIG. 2 is a side elevational view thereof, the opposite side being a mirror image of the side shown herein; and

FIG. 3 is an end elevational view thereof, the opposite end being a mirror image of the end shown herein.

I claim:

The ornamental design for a reproduction machine stacking cart, as shown and described.
